(57) **CLAIM**

The ornamental design for a motor connector component for a construction kit, as shown and described.

DESCRIPTION

FIG. 1 is a top and front perspective view of a motor connector component for a construction kit showing our new invention; FIG. 2 is a top and rear perspective view thereof; FIG. 3 is a bottom and front perspective view thereof; FIG. 4 is a bottom and rear perspective view thereof; FIG. 5 is front elevation view thereof; FIG. 6 is a rear elevation view thereof; FIG. 7 is a right side elevation view thereof; FIG. 8 is a left side elevation view thereof; FIG. 9 is a top plan view thereof; and, FIG. 10 is a bottom plan view thereof.
The broken line in the figure drawings is included for the purpose of illustrating unclaimed environment and forms no part of the claimed design.
